UNITED STATES PATENT OFFICE.

AXEL F. LARSON AND KARL O. OSTERGREN, OF CHICAGO, ILLINOIS, ASSIGNORS TO MARQUETTE PIANO COMPANY, OF CRYSTAL FALLS, MICHIGAN, A CORPORATION OF MICHIGAN.

SELF-PLAYING-PIANO MECHANISM.

No. 914,054.

Specification of Letters Patent.

Patented March 2, 1909.

Application filed February 19, 1908. Serial No. 416,797.

To all whom it may concern:

Be it known that we, AXEL F. LARSON and KARL O. OSTERGREN, citizens of the United States, residing at Chicago, in the county of Cook and State of Illinois, have invented a certain new and useful Improvement in Self-Playing-Piano Mechanism, (Case 2,) of which the following is a full, clear, concise, and exact description, reference being had 10 to the accompanying drawings, forming a part of this specification.

Our invention relates to self-playing pianos, and has for its object improved mechanism whereby the rewinding of the rolls of 15 music is effectually accomplished. It is well known in this class of pianos that the rolls contain several pieces of music, and our invention contemplates mechanism which will rewind the sheet of music after all of the 20 pieces thereon have been played. This being the primary object of our invention, there is also provided means whereby said sheet of music may pass over the tracker-board at varying speeds, so as to give the 25 desired effect to the music as it is being played.

Our invention will be clearly understood, reference being had to the accompanying drawings, in which—

30 Figure 1 illustrates the mechanism which is adapted to be placed inside of a piano directly beneath the keyboard; Fig. 2 is an elevation view of pneumatic mechanism used in conjunction with the mechanism shown 35 in Fig. 1; Fig. 3 is a top view of Fig. 2; Fig. 4 is a vertical sectional view, taken on line 4—4 of Fig. 3; Fig. 5 is a view taken on line 5—5 of Fig. 1; Fig. 6 is a view partly in section, taken on line 6—6 of Fig. 1; Fig. 7 40 illustrates mechanism for controlling a circuit in which is included a motor, this mechanism being used for starting the operation of the piano by means of the insertion of coins into a chute.

45 In Fig. 1 is shown supporting members 1 and 2, between which are supported the rolls 3 and 4; a music sheet 5 being shown for winding upon the roll 3 when the music is being played and being rewound upon the 50 roll 4 after all the pieces on said sheet have been played. In order to effect this desired result, there is provided a motor 6 having a shaft 7, to which is secured a worm gear 8 meshing with a worm wheel 9 which is fastened to a shaft 10 supported in bearings 11

and 12 on the motor, and 13 and 14 being bearings to further aid in supporting said shaft. During the operation when the music is being played, the shaft 10 rotates in the direction illustrated by the arrow 15. This shaft is connected by means of a universal joint 16 with a shaft 17 having cranks 18, with which arms 19, 19 are connected with the connecting members 20, 20, which are fastened to exhausters 21, 21, there being 65 shown but three of such exhausters, which are disposed behind a supporting board 22 to the front of which is secured a main bellows 23. Although these exhausters and bellows are old in the art, they will be explained 70 merely to make clear the purpose of our invention. To that end it may be stated that the air is exhausted out of the main bellows by means of the exhausters 21, 21, and to prevent said bellows from becoming 75 completely collapsed, there is disposed an L-shaped member 24 pivoted at 25, the end 26 engaging a roller 27 and the end 28 having a spring 29 secured thereto, the other end of said spring being fastened to a post 30. It 80 will be apparent that this mechanism prevents the collapse of said bellows, and consequently the air is withdrawn from the pneumatic mechanism 31, which will be later described, and with which the bellows 23 is 85 connected by means of the flexible pipe 32. The pneumatic mechanism 31 preferably consists of a supporting member 32', at each side of which are disposed bellows 33 and 34. A channel 35 passing through supporting 90 member 32' connects the bellows 33 with the compartment 36. A similar channel 37 communicates with the bellows 34 and with a compartment similar to 36, these compartments being disposed side by side, as will be 95 noted from Fig. 3. Each of these compartments is connected to the chamber 38 by means of openings 39 in the casing 40, and as the bellows 23 is in direct communication with this chamber, the air will be exhausted 100 therefrom. Each of these compartments is also connected to atmosphere through the openings 41 and 42. As clearly shown in Fig. 3, there are cross-pieces 43 and 44 which span these openings and are adapted for supporting stems 45 and 46. The construction of these parts is similar, and a description of one will serve as the description of the other, and therefore it may be stated that the stem 45 terminates in a plate 47, between which

2
and a washer 48 is disposed a flexible member or diaphragm 49, this member completely covering a chamber 50. The stem 45 has secured thereto a valve 51, which normally 5 closes the opening 39 leading from the compartment 36 and the compartment 38. There is shown a passageway 52 which leads from the compartment 50 and terminates in a metal tube 53, this tube being provided so as to form a connection for the rubber tube 106. Connecting compartment 38 and passageway 52 there is provided restricted channels 55. In order to limit the volume of air which will pass through these channels, there is 10 provided a screw 56, which is adapted to limit the size of the connection of said openings. Pivoted at 57 on the supporting member 31 there is shown a link 58, which pivots at 59 to an arm 60 which has connection with the bellows 33 and 34. The end 61 engages between members 62, which are secured to the rod 63 which may be supported in bearings 64, 64.

The right end of rod 63 terminates in members 65, between which is disposed a pin 66 which is secured to a vertical, rotatable shaft 67, this shaft being supported by means of brackets 68 and 69, which may be secured to the supporting member 1, as clearly shown in Fig. 1. At the upper end of the shaft there is provided a pin 70 which extends backward and engages in a slot 71 in the hub 72 of the sheave 73, which is slidably mounted upon the shaft 74 upon which the roll 4 is secured. Clutch mechanism 75 is employed so as to cause this sheave to be brought into driving relation with the shaft. A pin 76 is also secured to the shaft 67, and is adapted to engage in a slot 77 upon a hub 78 of the sheave 79. Clutch mechanism is also provided in connection with this sheave, and as shown in Fig. 1, is in driving relation with the shaft 80 which supports the roll 3. It is apparent that this mechanism provides the necessary means for alternately connecting and disconnecting the sheaves 73 and 79 with the shafts upon which they are mounted, and in order to secure the desired connection with the motor 6, there is provided a belt 81 which passes over a pulley or a sheave 82 which is securely fastened to the shaft 10. The shaft 10 terminates in a cone pulley 83, which is in frictional engagement with a pulley 84 mounted upon a shaft 85, this shaft being pivotally mounted in a supporting frame 86 which has arms 87 and 88 extending backward and secured to a shaft 89 by means of set screws 90, this shaft being pivotally mounted on the U-shaped frame 91. The shaft 89 has loosely mounted thereon pulleys 92 of different diameters and which are shown as being belted to pulleys 93. A belt 94 connects pulley 92 with the sheave 79. The shaft 85 is connected by means of a ball and socket joint 95 to a member 96 supported in the

bearing 97 and pivoted to a link 98 which terminates in a handle 99, which is adapted to extend into a slot in the key bed of the piano and is adapted to be actuated at the will of the operator. In order to cause the pulleys 83 and 84 to make proper engagement, there is secured to the frame 86 a spring 100, which is preferably secured to the supporting member, although any other means may be employed which will produce the desired result. After all of the pieces of music which are upon the sheet 5 have been played and are wound upon the roll 3, it is necessary to rewind the music on the roll 4, and to this end there is an opening 101 in said sheet which registers with the opening 103 in the trackerboard, the opening 104 being connected to the pneumatic mechanism by means of a flexible tube 105. A similar connection from the opening 103 is shown by means of the flexible tube 106.

The mechanism which forms the subject of our invention is preferably adapted to be started by the insertion of a coin into the piano, which coin passes through a chute 107 that leads to a receptacle 108 which may be disposed at any suitable place underneath the key bed of the piano. As clearly shown in Fig. 7, we have provided an arrangement by which the coin closes a circuit so that the motor 6 will cause the operation of the mechanism, and to that end we have pivoted at 109 a lever 110, which has secured thereto a contact spring 111 which, as shown in the drawing, is in engagement with a stud 112, the pivot 109 and the stud 112 forming the terminals of a circuit which has included therein the motor 6 and a source of current 113. The lever 110 engages in a slot 114 in a member 115, which is pivoted at 116 and 105 which has hinged at 117 a connecting member 118 which is secured to bellows 119 fastened to a supporting piece 120. Extending through the supporting piece is a channel 121 connected by means of a tube 122 to one of the pneumatics of the piano, which is clearly shown and described in our application Serial No. 302,765, allowed January 4, 1908.

The operation of this mechanism is as follows: When a coin is inserted into the piano, it passes through the chute 107 and strikes the lever 110 and throws it into the position as shown in full lines in the drawing. This closes the circuit, as shown, and causes the motor 6 to operate; consequently, through the afore-mentioned mechanism, the roll 3 will be rotated so as to draw the sheet 5 over the trackerboard, causing the operation of the piano. After each piece of music has been played, it is desirable to have the piano cease playing and to effect this an opening 123, of which there is provided one for each piece of music, registers with an opening 124 in the trackerboard which is connected by means of a tube 125 to the pneumatic above 120.

referred to. The operation of this pneumatic causes the bellows 119 to collapse, and consequently rotates the member 115 and allows the lever 110 to move into its dotted position, a spring 126 in this instance causing the lever to assume such position. This, it will be apparent, opens the circuit for the reason that the spring 111 becomes disengaged from the stud 112, and the circuit will not again be closed until another coin has been inserted into the chute, which coin will again throw the lever into the position as shown in full lines to close the circuit. In order to hold the member 115 so that the slot 114 will properly engage the lever 110, there is provided a spring 127 for this purpose. After the coin has been inserted and the circuit is closed, the operation which takes place is as follows: The motor is caused to operate, consequently the shaft 10 is rotated in the direction of the arrow 15 and the cone pulley 83 causes the pulley 84 to rotate, and by means of the pulleys 92 and 93 the sheave 79 is rotated in the direction of the arrow, as indicated. This, it will be seen, draws the sheet 5 over the trackerboard and consequently causes the piano to be played. As the music sheet passes over the trackerboard when the piano is being played, the passages 103, 104 and 124 are closed. The air is slowly withdrawn from these passages and the chamber 50 by virtue of the connection of chamber 38 through the restricted channels 55. After all the pieces contained on the sheet have been played, the opening 101 in the sheet registers with the opening 103, which causes air to rush through the openings through the tube 106, and through the metal tube 53 connected therewith, through the channel 52 and into the compartment 50. As the air has previously been exhausted from these parts owing to the connection of the channels 55 with the compartment 38 and the flexible member 49 maintained in the position as shown, it will be apparent that the air as it rushes into the compartment 50 lifts the stem 45 and the associated valve, and closes the opening 41 leading to the atmosphere. This establishes communication from the bellows 33 through the passageway 35, chamber 36, opening 39 and chamber 38, and as the bellows 33 is thus directly in connection with the main bellows 23, the air will become exhausted from the bellows 33 through the channel 35, chamber 36, passageway 39 and chamber 38, out through the flexible tube 32, thus causing the collapsing of the bellows 33, and as the bellows 34 is in communication with atmosphere, the air will rush into said bellows to inflate it, and as the bellows 33 is collapsed, there will be an action such as to cause the lever 58 to be swung about the pivot 57, thus shifting the rod 63 to the right, causing the vertical shaft 67 to rotate, and thus by means of the pin 70, the sheave 73 will be brought into driving relation with the shaft 74 and at the same instant the sheave 79 will be brought out of driving engagement with the shaft 80. This causes the roll 4 to be rotated in the direction 70 as indicated by the arrow, and causes a rewinding of the sheet of music. After the sheet has been rewound upon the roll 4, there are openings 102 which register with the opening 104 and cause the air to rush into 75 said opening and through the flexible tube 105 and to the pneumatic mechanism 31, and thereby actuating the valve connected with spindle 46 to close the opening 42 leading to atmosphere, the result being that the bellows 34 is brought into communication with the bellows 23 and the air exhausted therefrom through the channel 37, chamber 36, opening 39 and chamber 38 and pipe 32. During this action, the spindle 45 remains inert, and consequently the bellows 33 is in connection with atmosphere to cause inflation thereof. Simultaneously with this operation, there is an opening on the music sheet which registers with the opening 124, causing the actuation 80 of the pneumatic 119 to break the circuit and stop the motor. The mechanism will now be in position to start upon the insertion of a coin. When the rod 63 is shifted toward the right, there is provided a slide 128 which has 85 openings 129 which are brought out of register with the openings 130 of the air chest 131, which has connection with the pneumatics of the piano by means of a tube 132. This slide 128 is shifted by means of a pivoted member 133, which has connection to the shaft at 134, so that when said shaft is shifted toward the right, the openings 130 will become closed and the bellows will be used during such period to exclusively operate the 100 pneumatic mechanism 31 cutting off the pneumatics of the piano from the main exhaust 23 during rewind. Of course, when the music is being played the openings 129 in the slide are in register with the openings 130, 105 and cause the air to be exhausted out of the chest 131 so as to cause the proper actuation 110 of the pneumatics of the piano. It is frequently necessary when a piece is being played that the mechanism be given varying 115 speeds, and for this purpose the lever 98 is provided so that the pulley 84 can be shifted so that it will engage different areas of the cone pulley 83, thus securing a varying speed of the roll 3. 120

This mechanism, it will be apparent, provides a very simple arrangement to produce the desired result of shifting the mechanism so that the sheet of music will be rewound upon one roll after all the pieces thereon have 125 been played, and while we have shown but one embodiment of our invention, it is apparent that changes may be made without departing from the spirit and scope of our invention. 130

We do not, therefore, wish to limit ourselves to the precise construction herein described, but desire to secure by Letters Patent:

- 5 1. In combination, a self-playing piano, music rolls associated therewith, means for causing the operation of said rolls, a trackerboard, a music sheet adapted to pass over said trackerboard, pneumatic mechanism connected with said trackerboard, there being openings in said music sheet for causing operation of said pneumatic mechanism, bellows for connection with said pneumatic mechanism, means associated with said music rolls for causing their rotation in one direction when one of said bellows of pneumatic mechanism is inflated, said music rolls being caused to rotate in the opposite direction when the other of said bellows is inflated, and means for causing a varying degree of speed with which the music sheet passes over the trackerboard, said pneumatic mechanism comprising a central supporting member, bellows on each side of said member, there being channels extending through said member to connect to each of said bellows, valves connected with each of said channels, said valves being connected with the trackerboard, actuation of either 30 said valve causing the inflation of the bellows connected therewith.

2. In combination, a self-playing piano, music rolls associated therewith, means for causing the operation of said rolls, a trackerboard, a music sheet adapted to pass over 35 said trackerboard, pneumatic mechanism connected with said trackerboard, there being openings in said music sheet for causing operation of said pneumatic mechanism, said pneumatic mechanism comprising a central 40 supporting member, bellows disposed on each side of said member, there being channels extending through said supporting member and connected to said bellows, valve mechanism in connection with each of said channels, 45 means associated with said music rolls for causing their rotation in one direction when one of said bellows of the pneumatic mechanism is inflated, said music rolls being caused to rotate in the opposite direction 50 when the other of said bellows is inflated, and means for manually causing a varying degree of speed of said sheet of music as it passes over the trackerboard.

In witness whereof, we hereunto subscribe 55 our names this 13th day of February, A. D. 1908.

AXEL F. LARSON.
